UNITED STATES PATENT OFFICE

115,316

DESIGN FOR A SINK CABINET

John R. Morgan, Oak Park, Ill., assignor to Sears, Roebuck and Co., Chicago, Ill., a corporation of
New York

Application November 18, 1938, Serial No. 81,210

Term of patent 7 years

To all whom it may concern:

Be it known that I, John R. Morgan, a citizen of the Republic of Guatemala, residing at Oak Park, in the county of Cook and State of Illinois, have invented a new, original, and ornamental Design for a Sink Cabinet, of which the following is a specification, reference being had to the accompanying drawing, forming a part thereof.

The drawing shows a perspective view of a sink cabinet embodying my new design.

I claim:

The ornamental design for a sink cabinet, as shown.

JOHN R. MORGAN.
